LEONARD E. EASTMAN, OF SPRINGFIELD, MASSACHUSETTS, ASSIGNOR TO AMERICAN BOSCH MAGNETO CORPORATION, OF SPRINGFIELD, MASSACHUSETTS, A CORPORATION OF NEW YORK

SWITCHING MECHANISM

Application filed September 23, 1930. Serial No. 483,801.

This invention relates to switching mechanism, and more particularly to means of the character mentioned adapted especially for use in long wave-short wave radio receivers, whereby the said receiver may be switched from long wave to short wave reception, and vice versa.

10 The mechanism has been arranged with its principal objective the simultaneous actuation of a plurality of electrical switches, and the provision of a switch element which is both novel, simple and efficient.

15 The switch element comprises, preferably, an annular member having suitable metal contacts arranged to engage the terminals of an electrical element, reactance or circuit, and the said element is arranged to be actuated by a member connected thereto.

20 The switching mechanism comprises, preferably, manually operable means for reciprocating a suitable member whereby in turn the said switch element or a plurality of them may be simultaneously actuated, rotated or 25 oscillated to perform its switching function.

30 In the specific application above described, the metal contacts are arranged to be moved with the switch element into engagement or contact with terminals on one or more loading reactances of the receiver, whereby the same may be short-circuited to change the 35 reception from long wave to short wave.

The accompanying drawings illustrate my invention.

35 Fig. 1 is a plan view seen from the underside of Fig. 2 of my switching mechanism in combination with inductance reactances of a radio receiver; this figure being partly in section;

40 Fig. 2 is an elevation thereof appearing as if seen from the top of Fig. 1;

Fig. 3 is a top plan view of the complete switching mechanism in one position, and Fig. 4 in the opposite position; these views 45 being in sections taken along the line 3—4 on Fig. 2;

Fig. 5 is a view of the actuating bar for the switch mechanism; this view being partially in section along the line 5—5 on Fig. 50 ure 1, and

Fig. 6 is a circuit diagram of a radio receiver embodying my switching mechanism.

The switching mechanism comprises a manual member 1 mounted on a shaft 2 journaled in bearings 3, 4, mounted on base plate 5. The said shaft has rigidly mounted thereon and rotatable therewith a cam 6 provided with a slot 7 in which rides a pin 8 secured to switch bar 9. The switch bar is provided with spring clips 10, 10, provided with pins 11, 11, passing through holes in said switch bar. The said clips are arranged to receive perforated ears 13, 13, of the switch elements 14, 14, and the said ears are secured in said clips by the pins 11, 11, passing through the perforations in said ears.

The switch element is composed, preferably, of a ring or annular member 16 of insulative material, of which the ear forms an integral part. The said annular member rides in the groove 17 of a cylindrical member or cup 18 and the ear passes through a slot 19 in said cup. The annular member is provided with metal contacts 20, 20, connected by a conductor 21, which contacts are arranged to engage the terminals of a circuit or electrical element or loading reactance, such as the inductance coil to be hereinafter identified.

The operation of the switching mechanism is clear from the drawings and the description. Rotation of the shaft 2 in one direction or the other shifts the switch bar in one direction or the other as the case may be, and in turn the switch bar rotates the switch elements in one direction or the other as the case may be. The limit of oscillation or rotation of the switch elements is set by the side walls of the slot 19 in the cup. Thus, the shaft 2 and switch elements rotate only through an arc, and the reversal of movement of the shaft reciprocates the switch bar which in turn oscillates the switch elements. For the specific application herein described, the arc

need be only sufficient to have the metal contacts make and break contact with the terminals aforementioned. The slot in the cup will accordingly be of the dimensions necessary to delimit the required arc of oscillation of the switch element.

Referring now particularly to Figs. 1 and 2, there is shown a coil assembly 30 comprising a relatively short-wave inductance coil 31 mounted on a support or tubular form 31' at right angles to a loading coil 32 on a tubular form or support 32'. As shown in the circuit diagram Fig. 6 the said coils are connected in series, and the right angled disposition of the coils is indicated by the symbol identified as 33. The ends of the loading coil windings terminate in terminals 34, 34. The coil assembly is mounted at 35, 35, inside the annular switch element and the cup. The loading coil terminals are so aligned as to permit engagement or contact therewith by the metal contacts on the switch element when the latter is rotated in one direction and to be disengaged therefrom when said element is rotated in the other direction, as clearly shown in Figs. 4 and 3 respectively. The two metal contacts are electrically connected by conductor 21, so that the effect of the metal contacts engaging the terminals on the loading coil is to short-circuit the same, thereby changing the range of reception from long wave to short wave.

The circuit diagram Fig. 6 discloses a radio receiver having a plurality of tunable circuits 36 employing my switching mechanism, the parts therein corresponding to the mechanical elements of the switching mechanism being designated with reference numerals similar to that employed in the mechanical figures.

Having described my invention, what I claim is:

1. The combination of a circumferentially grooved cylindrical member, an annular member supported in said groove, metal contacts on said annular member, a coil, a support projecting into said annular member and carrying the coil, terminals on said coil, and means for actuating said annular member to make and break contact between said contacts and said terminals.

2. The combination of a circumferentially grooved and slotted cylindrical member, an annular member supported in said groove and having a part projecting through said slot, metal contacts on said annular member, a coil, a support projecting into said annular member and carrying the coil, terminals on said coil, and means engaging said projecting part for oscillating said annular member to make and break contact between said contacts and said terminals.

3. The combination of a base plate, a plurality of alined circumferentially grooved and slotted cylindrical members mounted thereon, annular rotary switch elements having their outer peripheries riding in said grooves and having ears projecting through said slots, metal contacts on said switch elements, coils, supports for said coils mounted inside said elements having terminals, and means engag-

ing said ears operable to actuate said elements to make and break contact between said contacts and said terminals.

4. The combination of a base plate, a plurality of alined circumferentially grooved and slotted cylindrical members mounted thereon, annular rotary switch elements having their outer peripheries riding in said grooves, ears on said switch elements projecting through said slots, inwardly disposed metal contacts on said elements, coils, supports for said coils mounted inside said switch elements and on said base, terminals on said supports, and a reciprocating member to which the ears are connected, whereby said switch elements may be actuated to make and break contact between said contacts and said terminals.

In testimony whereof I affix my signature.
